UNITED STATES PATENT OFFICE.

GEORGE H. SIMPKINS, OF LOUISVILLE, KENTUCKY.

COIN-CONTROLLED VENDING MACHINE.

Application filed June 6, 1925. Serial No. 35,368.

To all whom it may concern:

Be it known that I, GEORGE H. SIMPKINS, a citizen of the United States, residing at Louisville, in the county of Jefferson and State of Kentucky, have invented certain new and useful Improvements in Coin-Controlled Vending Machines; and I do hereby declare the following to be a full, clear, and exact description of the invention, such as will enable others skilled in the art to which it appertains to make and use the same.

This invention relates to coin controlled vending machines, and it consists of the novel construction, combination and arrangement of parts hereinafter fully described and claimed, and illustrated in the accompanying drawings, wherein:—

Figure 1 is a view in front elevation of a vending machine constructed in accordance with my invention,

Figure 2 is a sectional view taken on a plane extending vertically and centrally through the vending machine,

Figure 3 is a sectional view taken on the horizontal plane indicated by the line 3—3 of Figure 2,

Figure 4 is a sectional view taken on the vertical plane indicated by the line 4—4 of Figure 3,

Figure 5 is a detail perspective view of one of the article pushers,

Figure 6 is a detail perspective view of one of the guides for the article pushers,

Figure 7 is a detail top plan view of one of the guides and article pushers,

Figure 8 is a sectional view taken on the vertical plane indicated by the line 8—8 of Figure 2,

Figure 9 is a sectional view taken on the vertical plane indicated by the line 9—9 of Figure 7,

Figure 10 is a detail perspective view of one of the detents for the article pushers,

Figure 11 is a detail perspective view of the article follower, and

Figure 12 is an elevational view of the lower portion of the article chutes.

Corresponding and like parts are referred to in the following description, and designated in the several views of the accompanying drawings, by similar reference characters.

The casing of the vending machine comprises a bottom 1, a lower back section 2,

and sides 3 having upper portions 3^a of reduced width. These parts together with a forwardly projecting tray 4 are preferably integral. The front 5 of the casing is removably retained in place by lugs 6 formed integrally with the sides 3, and is provided with a mirror 7 and a horizontal row of sight openings 8 closed by glass panels 9.

The article carrier comprises a plate 10 which is bolted to the rear edges of the side portions 3^a and which is provided at its inner side with vertically extending angular members 11. These members together with the plate provide article receiving compartments 12 in front sides of which are vertical slots 13. The upper portion of the plate 10 constitutes the upper back section of the casing, and the lower portion thereof extends downwardly into the casing in forwardly spaced relation with respect to the lower back section 2. A top 14 is secured to the upper edge of the plate 10 by hinges 15, and it closes the upper ends of the casing and compartments 12. A lock 16 carried by the front 5 and engaging the top 14 prevents the unauthorized removal of the former and the unauthorized opening of the latter. A door 17 resting upon the inclined upper edges 18 of the sides 3, secured at its lower edge to the upper edge of the lower back section by hinges 19, and secured in closed position by a lock 20, is provided in order that free access may be gained to the dispensing mechanism of the machine for the purpose of inspection or repair.

The machine is especially designed for the purpose of vending cakes of soap in factories, offices and the like, and the cakes of soap 21 are arranged within the compartments 12 and supported therein by the front ends of guides 22. A downwardly and forwardly extending partition 23 is secured within the casing below the guides 22, and is adapted to direct the articles pushed from the compartments 12 into the tray 4. The partition 23 is provided with side flanges 24 to permit it to be bolted to the sides 3. A coin receiving drawer 25 is located within the casing in rear of the partition 23, and is removable through one of the sides 3. The drawer 25 is slidably mounted upon the bottom 1 between guides 26, and is provided with a lock 27 by which it is secured in closed position.

Each of the guides 22 comprises a plate 28 resting upon and bolted to a rib 29 formed integrally with the lower back section 2 and a flange 30 extending rearwardly from the upper end of the partition 23. The plates 28 are provided with side flanges 31, the front portions 31^a of which are higher than their rear portions 31^b. The flange portions 31^a are located within the lower ends of the compartments 12 and the articles 21 are supported directly thereby. The plates 28 are provided with openings 32 located above the drawer 25 so that when a coin is released from one of the pushers 33 it will fall into the drawer. The pushers 33 are slidably mounted upon the plates 28 between the flanges 31, and are provided with coin receiving slots 34 which gradually increase in width in the direction of the lower sides of the pushers. The pushers 33 are provided with horizontal grooves 35 which intersect the slots 34 and which open out through the ends thereof and receive coin stops 36. The coin stops 36 prevent the passage of coins through the slots 34 until the pushers 33 have been moved far enough to carry their slots 34 beyond the forward ends of the stops. When the pushers 33 reach this position the lower-most of the articles 21 will have been discharged from the compartments 12 and the coins will pass through the slots 34 and openings 32 into the drawer 25. The pushers 33 are yieldingly retained in retracted position against stops 37 by springs 38 secured to the pushers and lower back section 2, and when in this position there coin slots 34 are partly closed by the stops 36. The pushers 33 are adapted to be moved forwardly by pulls 39 of U-shape. The side members 40 of the pulls 39 pass through slots 41 in the compartment forming members 11 and lots 42 in the front 5, the slots 11 and lots 42 in the front 5, the slots opening out through the lower ends of the parts in which they are formed in order to permit the removal of the article carrier and the front 5. The inner ends of the pull members 40 are connected to trunnions 43 which are carried by the pushers 33, and they are secured to the trunnions by cotter keys 44. The cross members 45 of the pulls 39 provide hand grips, and secured to the pull members 40 between the pull members 45 and the front 5 are cross pieces 46 which when the pushers 33 are in normal position contact with the front 5. The pushers 33 are held against any but forward and rearward sliding movements on the plates 28 by the flanges 31 and the coin stops 36.

A gravity actuating detent 47 is provided for each pusher 33. The detents 47 rest upon the pushers 33, and have their rear ends pivoted as at 48 to the lower back section 2, and are provided at their forward

ends with depending hooks 49 which when the pushers 33 are in normal position occupy a position slightly forward of the front ends of the pushers. The detents 47 extend over the coin slots 34 and are notched as at 50 to accommodate the lower ends of coin chutes 51 which communicate at their lower ends with the slots. In their under sides the detents 47 are provided with cam portions 52 which are arranged slightly in advance of openings 53 in the front sides of the coin chutes 51. During the initial phase of the forward movement of the pushers 33, the upper edges of the coins contact with the cam surfaces 52 and raise the detents 47 far enough to carry their hooks 49 out of the path of the carriers. After the coins pass the cam portions 52 they contact with the under sides of the detents 47 and support the detents until the carriers 33 have been moved far enough to carry the coins beyond the front ends of the stops 36, whereupon the coins will pass through the slots 34 and openings 32 into the drawer 25 and the detents 47 will fall until their hooks 49 contact with the upper sides of the pushers 33. When the pushers 33 are released they will be returned to their normal positions by the springs 38, and when they reach such position the detents 47 will gravitate to their normal positions.

A follower 54 is mounted upon each stack of the articles 21, and carries a sign 55 bearing the word "Empty." When all of the articles 21 in any of the compartments 12 have been sold, the follower 54 will rest upon the flange portions 31^a with the sign 55 in front of the opening 8 registering with the empty compartment.

The distance that the stops 36 extend across the slots 34 depends upon the diameter of the coin representing the price of the articles 21, and this distance is such that the stops 36 will support a proper coin and thus permit the actuation of the pushers 33 while a smaller coin will pass freely through the slots 34 and openings 32 into the drawer 25.

All parts of the machine are made of metal, and the casing, article carrier, front 5, top 14, door 17, and partition 23 are preferably made of aluminum. If desired the machine may be used for vending articles other than soap.

From the foregoing description, taken in connection with the accompanying drawings, the advantages of the construction and of the method of operation of the vending machine will be readily apparent to those skilled in the art to which it appertains. While I have described the principle of operation of the invention, together with the device which I now consider to be the best embodiment thereof, I desire to have it understood that the device shown is merely

illustrative, and that such changes may be made therein when desired as are within the scope of the invention as claimed.

What is claimed is:—

- 5 1. A vending machine comprising a casing, an article carrier arranged therein, a plate located below the carrier and provided with an opening, a pusher slidably mounted upon the plate and provided with a
 10 coin receiving slot and a groove intersecting said slot, a coin stop entering said groove, a detent cooperating with the pusher and provided with a cam surface, a coin chute communicating with said coin slot and means
 15 for moving the pusher in opposite directions.
2. A vending machine comprising a casing, an article carrier located within the casing, a plate within the casing below the article carrier and provided with a slot, a stop carried by the plate, a pusher slidably mounted on the plate and provided with a coin receiving slot and a groove intersecting the slot, a spring normally holding the
 25 pusher in contact with the stop, a handle connected to the pusher and slidably mounted in the casing, a detent cooperating with the pusher and provided with a cam portion, a coin chute communicating with the coin slot, and a coin stop entering said
 30 groove.

3. A vending machine comprising an article carrier, a slidably mounted pusher provided with a coin receiving slot and a groove intersecting said slot, a coin stop entering said groove and extending partly across said slot, a detent cooperating with the pusher and provided with a cam surface, and means for moving the pusher in opposite directions. 35

4. A vending machine comprising an article carrier, a slidably mounted pusher provided with a coin receiving slot and a groove intersecting said slot, a stationary coin stop entering said groove and extending partly across said slot, and a detent cooperating with the pusher and provided with a cam surface, and means for moving the pusher in opposite directions. 40

5. A vending machine comprising a plate provided with an opening and flanges at opposite sides of the opening, a coin stop carried by one of said flanges and shorter than the opening, a pusher slidably mounted on the plate and provided with a coin receiving slot and a groove intersecting the slot and adapted to receive said stop, and pusher actuating means. 50

In testimony whereof I affix my signature.

GEORGE H. SIMPKINS.
